UNITED STATES PATENT OFFICE

DEIL DONOVAN, OF ST. LOUIS, MISSOURI

BATHROOM CABINET

Application filed June 8, 1928. Serial No. 283,929.

My present invention has reference to a medicine cabinet for bathrooms, and my object is to provide a cabinet of this type, which comprises a steel body having a non-chippable and non-breakable enamel surface, and which in addition to providing the cabinet with the usual shelves for the medicine and like bottles, the same has formed therein a receptacle and a valve controlled spout for delivering either hot or cold water, or a mixture of hot and cold water into the receptacle, the said receptacle being provided with an overflow pipe which is connected directly to the sewer, and is further provided on its outer face, adjacent to its bottom with a faucet whose spout portion is ribbed, whereby a douche tube may be attached thereto, the said cabinet being also provided with a compartment for the reception of the douche tube when the same is not required for use, together with a mirror-carrying hinged door of the same material as the cabinet for closing the said cabinet.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claim.

In the drawings:

Figure 1 is a front elevation of a cabinet in accordance with this invention in installed position, the door being opened.

Figure 2 is a sectional view approximately on the line 2-2 of Figure 1 with the door closed.

Figure 3 is a horizontal sectional view on the line 3-3 of Figure 1, looking in the direction of the arrows.

My improved bathroom cabinet comprises a box-like member 1 whose outer edges are provided with a continuous outwardly di-

rected rightangularly disposed flange 2. The cabinet is, of course, let in a suitable opening in the wall of the bathroom, and the sides of the cabinet contact with partition studs 3 in the wall construction and the cabinet is fixedly secured to said studs. The cabinet, on its inner faces, has its sides provided with angle cleats 4, upon which rest shelves 5 for medicine and toilet bottles or accessories. The cabinet is designed to be closed by a hinged door 6 whose frame carries a mirror 7.

The cabinet is, approximately in a line with the lower and short shelves, integrally formed with a receptacle 8. The receptacle extends from one side of the cabinet and the outer wall thereof or the wall adjacent to the short shelves, is indicated by the numeral 9. This wall is integrally formed with the back of the cabinet and extends a suitable distance above the top of the receptacle, the extending portion of the wall providing not only an end for one of the lower shelves but a splash board for the receptacle. The wall 9 has on the outer face thereof angle cleats 4' which, together with the cleats 4 support thereon the short shelves 5 of the cabinet and the said short shelves contacting with the wall 9 and one of the end walls of the cabinet brace the said wall 9 of the receptacle 8. Entering the bottom of the receptacle there is an overflow pipe 10 which is connected directly with a sewer pipe and whose top terminates a suitable distance from the top of the receptacle. The pipe 10 has screwed or otherwise secured thereon a flange or disc 10' which contacts with the bottom wall of the receptacle 8 and thereby tends to brace or support the said receptacle. Formed on what I will term the inner side of the receptacle and resting on the lower short shelf there is a box-like compartment 11. The receptacle is set a suitable distance inward with respect to the flanged edge of the cabinet and has its bottom inclined from its back to its front and its said front at its said bottom has attached thereto a faucet 12.

The mouth or outlet end of the faucet is provided with ribs 13 and the said ribs are designed to frictionally engage with the inner end of a rubber tube 14, the outer end

of the said tube having removably secured thereon a suitable attachment for douching or other purposes.

Between the walls of the bathroom there are pipes 15 and 16, respectively, one providing a conductor for hot water and the other for cold water. These pipes have their upper ends connected with a combined valve and mixing chamber 17 which is disposed adjacent and may be secured to the partition 3 adjacent the compartment 8. A common spout having a downwardly directed end indicated by the numeral 18 communicates with the chamber 17 and on the inner side of the cabinet above the spout there are handle members 19 and 20 for operating the valves in the chamber 17, to direct either hot or cold water or a mixture of hot and cold water through the spout 18 into the receptacle 8.

The steel cabinet has baked upon its entire exposed surfaces a heavy coat or coats of non-chippable and non-breakable enamel, the enamel being preferably white but, of course, may be differently colored and harmonize with the coloring of the bathroom in which the improvement is arranged. The compartment 11 may also serve as a receptacle for an antiseptic which may be mixed with the water in the receptacle.

My improvement is of a hygienic nature and not only serves as a cabinet for medicine bottles or the like but dispenses with the employment of the usual rubber douche or enema bag as well as with the enamel douche can which is commonly used in every household and hospital. Medicines rot and effect the rubber bags, while the enamel douche container like the rubber bag must have a nail or hook on which to hang in an elevated position. Many times the nail gives way and the result is a shower to the user and also the necessity of wiping or mopping the spilt contents after the accident. Should the ordinary enamel container or cabinet accidentally fall from position it necessarily becomes damaged, and the smallest piece of enamel flowing through with the fluid therefrom will cause an infection to the user. My improved cabinet is a permanent fixture, is pleasing to the eye, eliminates the embarrassment of a rubber bag or enamel container hanging in the bathroom or on the window sill as seen in many homes. The improvement also eliminates the filling of containers and finding a place to hang this necessary article which is used for sanitary and medical purposes. With my improved cabinet all that is necessary is to turn on either the hot or cold water or a mixture of hot and cold water and fix the hose on the faucet with the necessary attachment for the hose.

Having described the invention, I claim:

A bathroom cabinet having cleats on the side walls thereof to support shelves and

having formed therein a receptacle whose outer wall projects above the top thereof, and has secured thereon cleats to support the inner ends of short shelves, an overflow pipe passing through the bottom of the cabinet and entering through the bottom of the receptacle, a flanged element on said pipe contacting with the bottom of the receptacle and said receptacle having a valve controlled outlet and said receptacle being also designed for the reception of water that finds a passage through valve controlled pipes in one side of the cabinet.

In testimony whereof I affix my signature.

DEIL DONOVAN.
